UNITED STATES PATENT OFFICE

159,926

FIREPLACE TYPE RADIANT HEATER

James Leonard Raulston, South Pittsburg, Tenn.

Application August 4, 1949, Serial No. 4,300

Term of patent 7 years

(Cl. D81—10)

To all whom it may concern:

Be it known that I, James L. Raulston, a citizen of the United States, residing at South Pittsburg, in the county of Marion and State of Tennessee, have invented a certain new, original, and ornamental Design for a Fireplace Type Radiant Heater, of which the following is a specification, reference being had to the accompanying drawing, forming a part thereof, wherein:

The figure is a front perspective view of a fireplace type radiant heater showing my new design.

I claim:

The ornamental design for a fireplace type radiant heater, as shown.

JAMES LEONARD RAULSTON.
